UNITED STATES PATENT OFFICE.

EDWARD M. HEDLEY, OF DEPEW, NEW YORK.

PNEUMATIC TRACK-SANDER.

SPECIFICATION forming part of Letters Patent No. 705,757, dated July 29, 1902.

Application filed March 19, 1902, Serial No. 98,884. (No model.)

To all whom it may concern:

Be it known that I, EDWARD M. HEDLEY, a citizen of the United States, and a resident of Depew, in the county of Erie, State of New York, have invented certain new and useful Improvements in Pneumatic Track-Sanders, of which the following is a full, clear, and exact description.

This invention has relation to that class of pneumatic sanding devices used upon locomotives, trolley-cars, and like vehicles for delivering a stream of sand in front of the drive-wheels of the vehicle in order to prevent the slipping or skidding of the wheels.

The object of this invention is to provide a simple, durable, and effective construction of sander whereby the danger of the clogging of pipes from condensation or other causes will be prevented, and whereby a more effective delivery of the sand to the rails will be secured, and whereby also the cleaning or repair of the apparatus may be more readily accomplished.

The invention consists in the various features of improvement hereinafter described, illustrated in the accompanying drawings, and more particularly pointed out in the several claims at the end of this specification.

Figure 1 is a diagrammatic view of a locomotive-engine having my invention applied thereto. Fig. 2 is a detail view of the sander-casing, this view being a section upon line 2 2 of Fig. 3. Fig. 3 is a view in vertical section on line 3 3 of Fig. 4. Fig. 4 is a view in vertical section on line 4 4 of Fig. 3.

In Fig. 1 of the accompanying drawings my invention is shown as applied to a locomotive-engine, but it will be understood, however, that it may be employed upon trolley-cars, or, in fact, in any situation where a pneumatic track-sander is adapted for use.

A designates the body or casing of the sander. From this casing A a sand-delivery pipe B will extend to the sand-reservoir, which in the case of locomotive-engines is usually located above the boiler. From the casing A air-delivery pipes C and C' will lead to suitable valve mechanism within the engineer's cab. As such valve mechanism, however, forms no part of the present invention it need not be particularly described.

The sander-casing A will be connected to

the sand-delivery pipe B by a suitable coupling D, revolvably connected to the lower end of the pipe B and interiorly threaded to engage the exteriorly-threaded upper end of the neck a of the casing A. By this means the sander-casing A will be readily connected to and disconnected from the sand-delivery pipe B.

The neck a of the sander-casing A is provided with a cut-off valve E, this valve being adapted to be swung across the sand-admission orifice a' in the neck of the casing A, and thus prevent admission of sand to the casing when the latter is to be cleared or repaired. This feature of a cut-off valve at the top of the casing is an important one, as it enables the sand to be quickly shut off from the main supply whenever repairs are to be made or the casing is to be cleaned without necessitating the disconnection of the sander-casing and without the wastage of sand from the reservoir. As shown, the upper part of the casing A is formed with an offset-chamber E', adapted to receive the cut-off valve E, which when the sander is in operation will occupy the position shown more particularly in Fig. 2 of the drawings. The offset-chamber E' is preferably formed as an integral part of the casing A, the chamber E' being cored in the process of casting.

In order to permit the cut-off valve E to be inserted into the chamber E', a slot e will be cut through the wall of the casing, as more particularly indicated in Fig. 2 of the drawings, this slot being preferably of the quadrant or triangular shape there shown. The cut-off valve E will be inserted through the slot thus formed, and the edge of the opening e will be closed by a strip e', that will be held in position by suitable pins or screws e'', that will pass through the horizontal walls of the chamber, as indicated more particularly in Fig. 2 of the drawings. The check-valve E is formed with a polygonal opening adapted to receive the valve-stem E'', that will be inserted through the horizontal wall of the chamber E', as clearly shown in Fig. 3 of the drawings. The outer portion of the check-valve stem E'' will be fitted with a handle E'', whereby the valve may be conveniently manipulated, and against that part of the stem E'' outside the chamber E' will bear a spring

E', the valve-stem E² being formed with an annular recess e³ at such point. One side of that part of the valve-stem E² exposed to the bearing of the spring E³ will be flattened, 5 and this flattened portion will be so situated that when the cut-off valve E is in its normal open position the free end of the spring E³ will bear against the flattened portion of the valve-stem, and thus serve to hold the check-
10 valve E in open position and effectively guard against accidental closure of the valve. The spring E³ will be fastened, as by screws e⁴, (shown by the dotted lines in Fig. 2,) to that part of the valve-casing E immediately beneath the chamber or extension E'. It will thus be seen that the valve E will be completely closed in, so that all danger of access 15 of water to the interior of the casing at such point will be effectively prevented, while at the same time the valve may be shifted by means of the handle E³ whenever it is desired to shut off the supply of sand to the sander-casing—as, for example, when the sander is to be cleaned or repaired.
15 The body of the sander-casing A is divided by a vertical diaphragm A², that extends to a point immediately beneath the sand-administration opening a' in the neck of the casing, and as this diaphragm is arranged centrally beneath the opening a' the supply of sand will be delivered to the chambers A³ and A⁴ at each side of the diaphragm. Each of the chambers A³ and A⁴ is formed with a curved bottom a⁵, and beneath the chambers A³ and A⁴ extend the air-delivery channels a⁶ and a⁷. As shown, these channels a⁶ and a⁷ are of segmental shape, and as they are the same in construction one only is illustrated in the drawings. In fact, it will be readily perceived that the two portions of the sander-casing A lying upon opposite sides of the diaphragm A² are substantially duplicates one of the other, the purpose of this arrangement being to enable the chamber and adjunctive devices at one side of the diaphragm A² to be used for delivering sand to the track when the locomotive or car is moving in forward direction, while the chamber and adjunctive devices at the opposite side of the diaphragm A² will be brought into operation for delivering sand to the rail when the locomotive or car is moving in backward direction. I wish it understood also that while in the preferred embodiment of the invention 45 the sander is provided with duplicate chambers manifestly features of the invention may be employed where a single chamber only is used.

The channels a⁶ and a⁷ beneath the chambers A³ and A⁴ are provided, preferably, at their bottoms with ports, to which will be fitted the ends of the air-delivery pipes C and C', respectively, and at the end of each of the channels a⁶ and a⁷ will be placed an air-jet nozzle G, adapted to direct a jet of air downward in diagonal direction into the corresponding chamber A³ or A⁴. The opposite

end of the channels a⁶ and a⁷ will be provided each with an air-jet nozzle H, arranged opposite the outlet a⁸ from the corresponding chamber A³ or A⁴. To the outlet a⁸ of the chamber A³ connects a sand-discharge pipe K, that will lead to a point adjacent the rail or track in front of the forward wheel of the locomotive or car, and to the corresponding outlet a⁹ of the chamber A⁴ will be connected a similar sand-delivery pipe K', that will lead to a point adjacent the track or rail at a point behind the traction-wheel of the locomotive or car, as shown more particularly in Fig. 1 70 of the drawings. In the upper part of each of the chambers A³ and A⁴ is arranged a deflecting arch-plate a¹⁰, that is preferably curved downward toward the center of the chamber, as clearly shown in Fig. 4 of the 75 drawings, the purpose of this plate a¹⁰ being to effect a whirling movement of the sand in front of the discharge-opening a⁸ before it is forced down the discharge-pipe leading from the sander-casing. For convenience in cleaning and as well also to permit the insertion of the steam-jet nozzles suitable screw-threaded openings closed by the plugs M and N are formed in the walls of the casing A.
80

From the foregoing description the operation of my improved sander will be seen to be as follows: If it is desired to sand the track in front of the locomotive-wheels, the operator will, by the manipulation of suitable valve mechanism in the cab, cause air to pass through the air-delivery pipe C into the channel a⁶ beneath the chamber A⁴ of the casing. Air thus delivered to the channel a⁶ will pass through the contracted openings of the air-jet nozzles G and H. The air escaping through the nozzle G will cause the whirling motion of the sand within the chamber A⁴, thereby driving the stream of sand into the path of the jet of air passing from the nozzle H and causing the air to discharge into the pipe K that leads from the chamber A⁴ to the track. In like manner if it is desired to deliver sand to the track at the rear of the traction-wheels of the locomotive the engineer will cause air to pass through the air-delivery pipe C' into the channel a⁷ beneath the chamber A³, and from this channel a⁷ the air will be discharged through the corresponding air-jet nozzles G and H and sand will be discharged from the chamber A³ through the sand-discharge pipe K', that leads to the pipe at the rear of the traction-wheels. The employment of supplemental air-jets G for each of the chambers A³ and A⁴, if two chambers be used, together with the shape of these 90 chambers, has the effect of producing such a whirling or agitation of the sand within the chambers as to cause the sand to pass with even distribution into the outlet a⁸, where it will be caught by the jet of air passing through the nozzle H, and all danger of the clogging of the sand-discharge pipes is thereby effectively avoided.
95

When it is desired to clean the interior of

the sander-casing, the engineer will close the valve E, so as to cut off the supply of sand through the sand-delivery pipe B. The plugs M and N may then be removed and the interior of the casing cleaned without danger of wasting sand or without the necessity of emptying the sand-reservoir.

A further marked advantage incident to my invention is that the sander-casing being formed as a single casting it can be conveniently set in place or removed without danger of parts being lost or misplaced.

While I have set forth what I regard as the preferred embodiment of my invention, I wish it distinctly understood that the details of construction may be modified within wide limits without departing from the spirit of the invention and that features of the invention may be employed without its adoption as an entirety.

Having thus described my invention, what I claim as new, and desire to secure by Letters Patent, is—

1. A pneumatic track-sander comprising a casing having an opening for connection with the sand-reservoir, an opening for connection with the sand-discharge pipe and an opening for connection with the air-delivery pipe, of a valve movable transversely of said opening that leads to the sand-reservoir and a casing at one side of said last-mentioned opening to receive said valve when moved to open position, and a stem leading outside said valve-casing whereby said valve may be shifted.

2. A pneumatic track-sander comprising a casing having an opening for connection with the sand-reservoir, an opening for connection with the sand-discharge pipe and an opening for connection to the air-delivery pipe, of a valve for closing the opening that connects with the sand-reservoir, a chamber wherein said valve is inclosed, said chamber being formed with a slot to admit the valve, and a strip for closing said slot or opening of the chamber.

3. A pneumatic track-sander comprising a casing having an opening for connection with the sand-reservoir, an opening for connection with the sand-discharge pipe and an opening for connection with the air-delivery pipe, of a valve located in said casing and adapted to close the opening for the admission of sand, a handle connected with said valve and arranged upon the outside of said casing and a spring for holding said valve in open position.

4. A pneumatic track-sander comprising a casing having an opening for connection with the sand-reservoir, an opening for connection with the sand-discharge pipe and an opening for connection with the air-delivery pipe, of an air-jet nozzle or port for agitating the sand within the casing and an air-jet nozzle or port for causing the passage of sand through the sand-discharge pipe.

5. A pneumatic track-sander comprising a casing having an opening for connection with the sand-reservoir, an opening for connection

with the sand-discharge pipe and an opening for connection with the air-delivery pipe, of an air-delivery channel extending partially around the sand-receiving chamber of said casing, an air-jet nozzle or port adjacent one end of said air-delivery channel and adapted to deliver a jet of air to agitate the sand, and a second air-jet nozzle or port at the opposite end of said channel and adjacent the opening of the casing that leads into the sand-discharge pipe, whereby the sand will be forced through said pipe.

6. A pneumatic track-sander comprising a casing having a sand-receiving chamber, an opening above said chamber, for connection with the sand-reservoir, an opening leading from said chamber at one side of said casing for connection with the sand-discharge pipe, an air-delivery channel beneath and extending partially around said chamber, an air-jet nozzle or port at the upper end of said channel and arranged to deliver air obliquely downward into said chamber, a second air-jet nozzle or port arranged at the end of said air-delivery channel opposite said sand-discharge opening and an air-delivery pipe connected to said channel.

7. A pneumatic track-sander comprising a casing having a sand-receiving chamber therein, an opening above said chamber for connection with the sand-reservoir, an opening at one side of said chamber for connection with the sand-discharge pipe, a deflector-arch arranged between said sand-admission opening and said sand-discharge opening, an air-jet nozzle or port arranged on the opposite side of the chamber from said deflector-arch and a pipe for delivering air to said air-jet nozzle or port, whereby a whirling movement of the sand within the chamber will be effected.

8. A pneumatic track-sander comprising a casing having an opening for connection with the sand-reservoir, an opening for connection with the sand-discharge pipe and an opening for connection with the air-delivery pipe, of a deflector-arch arranged within said casing, an air-jet nozzle or port for agitating the sand within the casing, said port being arranged at a point opposite said deflector-arch and a second air-jet nozzle or port arranged opposite the sand-discharge opening of said casing.

9. A pneumatic track-sander comprising a casing having an opening at its top for connection with the sand-reservoir, a vertically-disposed diaphragm arranged beneath said opening and dividing the casing into two chambers for receiving sand, a sand-discharge port leading from each of said chambers and individual air-delivery pipes and air-jet nozzles or ports for said chambers.

10. A pneumatic track-sander comprising a casing having at its top an opening for connection with the sand-reservoir, a diaphragm beneath said opening and dividing the casing into two sand-receiving chambers, each of which chambers is provided with a sand-discharge port, a deflector-arch within each of

said chambers, an air-jet nozzle arranged adjacent the discharge-port of each of said chambers and serving to eject the sand therefrom, and an air-jet nozzle or port arranged within each of said chambers opposite said discharge-port for agitating the sand before it is discharged from the casing.

11. A pneumatic track-sander comprising a casing having an opening at its top for connection with the sand-reservoir, a vertically-disposed diaphragm beneath said opening and dividing said casing into two sand-receiving chambers, each of which chambers is provided with a sand-discharge port, a deflector-arch arranged within each of said chambers above said discharge-port, air-delivery channels extending beneath and partially around said chambers, each of said channels being provided at its upper end with an air-jet nozzle or port for delivering air to agitate

the sand within the chamber and at its opposite end with an air-jet nozzle or port for delivering a jet of air to eject the sand from the casing, and air-delivery pipes connected with said channels.

12. A pneumatic track-sander comprising a casing having an opening for connection with the sand-reservoir, an opening for connection with the sand-discharge pipe and an opening for connection with the air-delivery pipe, of an air-jet nozzle for agitating the sand within the casing and an air-jet nozzle for causing the passage of sand through the sand-discharge pipe, said air-jet nozzles being removably held in position within said casing. 25 30
